VACUUM TUBE AMPLIFIER SYSTEM

Philip E. Edelman, Chicago, Ill., assignor, by
mesne assignments, to Robert T. Mack, trustee,
Chicago, Ill.

Application February 20, 1928. Serial No. 255,814

1 Claim. (Cl. 179—171)

Good amplification via a sequence of vacuum tubes requires that the input energy be amplified without undesired amplification of side noises represented in the input energy and the partially amplified energy. This invention has for its object to increase the fidelity of responsive amplification to the desired portion of the input energy while excluding the undesired portion thereof from the amplified output, and is a continuation in part of my original application S. No. 566,132, filed in the United States Patent Office June 5, 1922, which became Patent No. 1,665,847.

The elements of an amplifier system are well known in the prior art but I have conceived that improved results may be had by a new and useful combination of the parts. I illustrate by way of example a suitable embodiment of my invention in the accompanying drawing which is a schematic diagram showing the invention applied to a sequence of vacuum tubes.

An amplifier of the class described includes means to select input energy, usually at high frequency, a convertor or detector stage to change energy amplified therefrom to lower frequency bands, and a further amplifier for the last named energy.

Heretofore selection between desired and undesired input energy has been sought by selective tuning means introduced in or ahead of the input to the amplifier and tuned to a particular high frequency band. It is known that all such selecting means or filters absorb and dissipate considerable energy so that the degree of selection or pre-filtering prior to amplification is very limited when the input energy is feeble. From considerations showing that an effective filter can be had to handle larger amounts of energy where the filter or selector losses are insufficient to bar efficient transfer of amplified energy, I prefer to arrange only a partial selector ahead of the amplifier input, permitting both desired and undesired energy to be amplified up to a certain stage, and then to introduce a power type filter or selector to further selectively amplify the aforesaid amplified output. In this manner, feeble input energy can be effectively amplified with suppression of undesired noises from the last amplifier stage output. Various changes and modifications may be made without departing from the idea of the invention and within the scope of the appended claim.

Referring to the drawing, input energy for the amplifier can be selected from either the aerial 1 or the power line 4, 5 by means of attachment plug 9 which fits in either socket 8 or 2 as may

be desired. When socket 8 is used, wires 7, 6, connected to line 4, 5, one of which is grounded at 3, serve to conduct carrier frequency energy intercepted thereby, to plug 9. A switch 13 permits switch arm 14 to connect with either conductor 11 or 12 from plug 9. High frequency energy can pass from switch arm 14 through the wire 10, fuse 15, fixed condenser 16 and tuning condenser 17 thru coils 18 and 19 and thence via wire 25 to ground 36. Radio frequency energy passing thru coils 18 and 19 will induce similar energy in coils 24 and 23 coupled thereto as controlled at conducting terminals 20, 39 by variable condenser 21. A by-pass condenser 27 connects through the wire 28 to coil 19 and also connects to coil 24 and 60 conducting plate 31. A selector or filter coil 22 connects to condenser 21 and coil 23 and can feed energy to grid input wire 26 of vacuum tube 99. Partially selected energy obtained through the plug 9 can thus be used to control the input 65 to the first vacuum tube 99, though some energy other than desired and selected may force itself thru filter coil 22.

Each vacuum tube 99, 96, 56 and 53 has the customary three elements, filament, grid and plate 80 respectively, and a fourth control element 58. All of the control resistances 58 connect to common plate conductor 31 at 55, 60, and 54, respectively. Conductor plate 31 connects through the wire 37 to filament power supply 41 and switch 85 35 controls the current fed therefrom through the wire 34, resistance 33, rheostat arm 32, wire 30 and the wires 29, 100, 101, and 65 respectively. A plate power supply source 38 connects via wire 40 to wire 37 and thence to conductor plate 31, 90 and suitable potential taps therefrom are provided at 42, 43 and 44 to feed current via wires 57 and 45 respectively.

Plate current for vacuum tube 99 is fed through the wire 57, resistance 87, wire 86, wire 90, switch 95 arm 91 and tapped coil 92 and its terminal wire 98. A by-pass condenser 95 connects through the wire 93 to switch arm 91, and through the wire 97 to conductor plate 31. Radio frequency energy selected from plug connector 9 and partially filtered by coil 22 may thus be converted and amplified by vacuum tube 99 with appropriate adjustment of coil 92, so that the amplified radio frequency energy from vacuum tube 99 will mainly flow thru condenser 95 while the converted frequency component of the amplified output thereof can flow to conductor plate 31 through the wire 90, wire 86, resistance 87, wire 57, power supply 38 and wires 40, 37. In so flowing thru resistance 87 at lower converted band of fre- 100 105 110

quencies controlled by vacuum tube 99, similar potentials will be set up at wire 89 connected to wire 90 and can pass to grid input wire 94 of vacuum tube 96 via controlling condenser 88. A shunt resistance 85 connects to input wire 94 and also connects to conductor plate 31 through the wire 84. The input 94 to vacuum tube 96 is thus responsive to all the bands of frequencies conducted thereto. Vacuum tube 96 receives plate current via path 50, resistance 80, wire 79, wire 86, resistance 87, and wire 57 connected to battery 38 at terminal 42. The amplified output energy from vacuum tube 96 passing thru resistance 80 causes potential to be transferred to condenser 81 to influence grid input wire 102 of vacuum tube 56. Wire 102 also connects via resistance 83 to wire 104 and thence to conductor plate 31. Vacuum tube 56 receives plate current supply from power source 38 via switch 43, wire 45, wire 66, resistance 70, wire 82 and wire 103. The amplified currents passing thru resistance 70 are able to apply potential to condenser 69 which connects with grid input wire 67 of vacuum tube 53. A shunt resistance 68 also connects wire 67 to conductor plate 31.

A filter circuit comprised by condenser 72, and condenser 71, with condenser 71 shunted by impedance coils 76 and 75, also interconnects wire 103 of vacuum tube 56 to resistance 68 and 70. Coil 75 connects through the wire 74 to one terminal 78 of condenser 71 while coil 76 connects to the other terminal 77 thereof and to one terminal of condenser 72. Most of the energy passing to wire 67 of vacuum tube 53 must pass thru this filter section between vacuum tube 56 and vacuum tube 53 and energy at frequencies barred by filter coils 76 and 75, with condensers 71 and 72, can only affect grid input wire 67 in minute amount compared with the desired energy input fed thereto, thereby. An effective input power filter for vacuum tube 53 is thus provided at a stage where the filter losses are small on the energy to be amplified, so that vacuum tube 53 serves substantially only as an amplifier for the desired pre-amplified and filtered energy made available by vacuum tube 56 and the aforesaid circuits connected thereto. Vacuum tube 53 can thus supply output energy through the wire 64, wire 52, battery 51, wire 61, reproducer 49 with its horn 48, wire 46 connecting at junction 47 to wire 45, and thence to plate current supply 38. Thus the undesired energy which is amplified through the vacuum tubes 99, 96 and 56 in order to simultaneously build up a large value of amplified energy which is desired, is selectively filtered at the stage where filter losses on the desired energy input are unimportant owing to the amplified value thereof, permitting power filter 76, 75, 71, 72 to efficiently select the input supplied to grid connection 67 of amplifier vacuum tube 53. Undesired energy forced thru coil 22 and amplified in vacuum tubes 99, 96 and 56 is thus so greatly diminished at the input wire 67 with respect to the desired energy, simultaneously

applied at wire 67, that the output wire 64 of vacuum tube 53 carries substantially no energy amplified at the frequencies barred by said power filter 75, 76, 71 and 72. This arrangement thus provides effective amplification of the desired energy and permits the values of coils 76, 75, condensers 71 and 72 also resistances 68 and 70 and condenser 69 to be selected to suppress and dissipate amplified values of predetermined frequency bands, while passing energy of desired pre-selected frequency band.

It will be observed that conductor plate 31 serves as an equal potential junction between the vacuum tubes 99, 96, 56, and 53, not grounded except through the condenser 27. There is thus shown a suitable embodiment illustrating the practice of the invention whereby input energy to the first of a series of vacuum tubes is partially selected and amplified along with undesired energy in order not to lose too much of the desired energy; then after the desired energy has been subsequently amplified to a large amplitude, a power filter or band selector circuit is used in the input to the last vacuum tube of the series in order to substantially bar final amplification of any but the desired energy represented in the selected band. It may be remarked that this arrangement produces surprising results and makes effective use of the characteristics of each vacuum tube 99, 96, 56 respectively, which are able to amplify the energy input thereto respectively only to the ability of each said tube, thus permitting the weaker desired energy represented in the finally selected band of frequencies to overtake, so to speak, the undesired bands and be effectively selected finally by the power filter set forth in the final amplifier input to vacuum tube 53.

The constants of the circuits will be designed in accordance with the bands to be barred and selected as is customary in the art and suitable formulae therefor may be found in U. S. Patent No. 1,127,113, also 1,127,114. The invention is applicable to a radio receiving system, or the like, and is more particularly pointed out in the appended claim.

I claim:

In an amplifier system of the class described, means to couple two vacuum tube amplifier stages each having plate and grid circuits comprising a band filter network composed of a first resistance in the plate circuit of the first vacuum tube, a second resistance in the grid circuit of the second vacuum tube, a condenser joining said first resistance to the grid of said second vacuum tube, two condensers in series connecting the plate of said first vacuum tube to said second resistance, an inductance shunted around one of said last named two series condensers, means to feed operating plate current through said first resistance, and means to conduct operating grid potential through said second resistance.

PHILIP E. EDELMAN.
